METHOD OF TREATING DERMATOLOGICAL
CONDITIONS

Edward H. Bowen, Jr., Evanston, Ill., assignor to
Baxter Laboratories, Inc.
No Drawing. Filed Jan. 3, 1961, Ser. No. 80,025
5 Claims. (Cl. 167—55)

The present invention relates to treatment of dermatological conditions. More particularly, it relates to the use of compositions not heretofore employed or recognized as effective in the treatment of acne vulgaris and related conditions.

Acne vulgaris and similar dermatological conditions, because of their common occurrence during puberty, and other periods when the thyroid gland is not assuming its full physiological function, have long been suspected by various clinicians as being related to faulty lipid metabolism. See Sutton, R. L., Jr., *Acne Vulgaris, a pustular lipoidosis*; South, M. J., 34: 1071 (1941).

Until the present, it has been generally believed that the power of thyro-mimetic materials to favorably affect lipid metabolism and improve conditions such as acne has been inseparable from their undesirable property of increasing the basal metabolic rate.

It has now been unexpectedly discovered that the administration of the d-isomer of a compound, the l-isomer of which is thyromimetic, produces beneficial effects in the treatment of acne vulgaris and other dermatological conditions with negligible increase in the basal metabolic rate.

In accordance with this invention, dermatological conditions are treated by administering compositions comprising a d-isomer of thyroxine or of a compound the l-isomer of which is thyro-mimetic in pharmaceutical dosage form. The d-isomer may be associated with any pharmaceutical carrier suitable for the preparation of compositions in dosage form. For purposes of illustration, the invention is described with particular reference to d-thyroxine. It is understood, however, that the scope of the invention is not limited to d-thyroxine, but includes d-isomers of compounds, such as 3,5,3'-triodothyronine and 3,5,3'-triodo-5'-methyl thyronine. It is further understood that the compositions employed in the practice of this invention are substantially free of therapeutically significant calorogenic amounts of thyro-active compounds of the l-series. It is desirable that the compounds used in the methods of this invention be substantially devoid of thyro-active material, i.e., material which engenders in the individual an effect on basal metabolic rate (BMR) analogous to that engendered by l-thyroxine. Such material normally comprises compounds of the l-series.

The compositions of this invention may take the form of tablets, powders, capsules or other dosage forms. The compositions employed in the methods of this invention may take the form of active material, namely, d-thyroxine, admixed with solid diluents and/or tableting adjuvants such as cornstarch, lactose, talc, stearic acid, magnesium stearate, gums or the like. Any of the tableting materials used in pharmaceutical practice may be employed where there is no incompatibility with the d-thyroxine. The material may be tableted with or without adjuvants. Alternatively, the d-thyroxine material with its adjuvant material may be placed in the usual capsule or resorbable material, such as the usual gelatin capsule, and administered in that form.

The d-thyroxine in particular has been found to have an insignificant effect on the basal metabolic rate of the individual at doses of 4-8 mgm./day and yet possess the ability to aid in the treatment of acne vulgaris and the like. Surprising therapeutic results are generally obtained through daily doses of d-thyroxine and its pharmaco-

2

logically acceptable salts in the range from 2 to about 8 milligrams. Higher doses may be administered in certain individuals with no undesirable BMR effects. Examples of these therapeutically active salts are the alkali metal salts of d-thyroxine such as sodium d-thyroxine, potassium d-thyroxine, d-thyroxine hydrochloride, and the like.

A more comprehensive understanding of this invention is obtained by reference to the following examples:

EXAMPLE I

10	Tablets, each containing the following amounts of ingredients, were prepared:		
	Sodium d-thyroxine	mg.	4.0
	Lactose	mg.	62.8
15	Powdered sugar	mg.	62.8
	F.D. and C. Yellow No. 5	mg.	0.037
	5% acacia solution, q.s.		
	Magnesium stearate	mg.	1.08
	Mineral oil	cc.	0.00092
20	Talc, q.s., approx.	mg.	2.9

EXAMPLE II

Tests were conducted to determine the calorogenic effect of the tablets prepared in Example I on normal human volunteers. Volunteers receiving maximum daily doses of 3, 4 and 5 mg. of d-thyroxine for periods as long as 75 days experienced only slight increases in basal metabolic rate.

To demonstrate the efficacy of the d-thyroxine in treating dermatological conditions the following representative clinical case histories are submitted:

Case No. 1

35 A white unmarried female, age 26, suffering from acne vulgaris received 2 mg. of d-thyroxine twice daily for approximately 4 months. Medication was then reduced to 2 mg. daily. The acne vulgaris was kept under control during this time but flared when medication was discontinued.

Case No. 2

40 A white male, age 64, suffering from follicular pustules received 2 mg. of d-thyroxine twice daily for approximately 2½ months during which period his dermatological condition improved.

Case No. 3

45 A white female, age 70, suffering from xanthelasma received 2 mg. of d-thyroxine twice daily for 2 months during which period her condition improved.

Case No. 4

50 A white male, age 37, suffering from psoriasis and xanthelasma received 2 mg. of d-thyroxine twice daily for 5 weeks and then twice daily for 5 weeks during which period the patient's dermatological condition improved.

Case No. 5

55 A white male, age 34, suffering from xanthelasma received 2 mg. of d-thyroxine thrice daily for 9 months during which period his condition was generally much improved and very few lesions recurred.

Case No. 6

60 A white unmarried female, age 57, suffering from xanthelasma received 2 mg. of d-thyroxine twice daily for 3 weeks. Patient reported feeling less "bloated" since taking medication and was pleased with progress.

Case No. 7

65 A white male, age 15, suffering atopic dermatitis and contact dermatitis received 2 mg. of d-thyroxine twice

daily for 9 weeks during which period the dermatological conditions, in general, improved.

Case No. 8

A white female, age 42, suffering from lichen planus and stasis dermatitis received 2 mg. of d-thyroxine twice daily for 5 weeks then 2 mg. once daily during which period the patient's dermatological condition generally improved.

Case No. 9

A white female, age 53, suffering from a condition diagnosed as intertrigo onychomycosis received 2 mg. of d-thyroxine twice daily for 4 months during which period the patient's dermatological condition generally improved. More specifically, a clearing of the afflicted hand areas was noted.

Case No. 10

A white female, age 41, suffering from seborrheic dermatitis and blepharitis marginalis received 2 mg. of d-thyroxine twice daily for 2 weeks at the end of which period her dermatological condition was much improved.

Case No. 11

A white male, age 27, suffering from necrobiosis lipoidica diabetorum received 2 mg. of d-thyroxine twice daily for 18 weeks at the end of which time he was doing well and his general appearance was improved.

Case Nos. 12-22

Ten patients both male and female, of various ages, suffering from psoriasis received 2 mg. of d-thyroxine twice and thrice daily. Of the 10 patients treated 7 improved, including one patient who had a history of psoriasis for 35 years.

While for purposes of illustration the inventive method has been described in relation to the use of d-thyroxine,

similar results are obtainable with d-tri-iodothyronine and the like.

It is apparent from the foregoing case histories that the d-isomers of compounds the l-isomer of which is thyro-mimetic e.g. d-thyroxine, d-tri-iodothyronine and the like, are valuable additions to the dermatologists' arsenal for the treatment of acne vulgaris, psoriasis, xanthelasma, xanthomatosis and a wide variety of related dermatological conditions in which aberrant lipoid metabolism may play a role.

The embodiments of the invention in which an exclusive property or privilege is claimed are:

1. In the treatment of patients afflicted with acne vulgaris the improvement which comprises administering to said patients d-thyroxine in an amount from about 2 to about 8 mg. daily.

2. The improvement in the treatment of dermatological conditions which comprises administering to a patient suffering from a dermatological condition of d-isomer of a compound selected from the class consisting of thyroxine, 3,5,3' - tri - iodothyronine, and 3,5,3' - triiodo - 5' - methyl thyronine.

3. The method of claim 2 in which the d-isomer is d-thyroxine.

4. The improvement in the treatment of humans having dermatological conditions which comprises administering to said humans a daily dosage in tolerated levels of a d-isomer of a compound selected from the class consisting of thyroxine, 3,5,3'-tri-iodothyronine, and 3,5,3'-triiodo-5'-methyl thyronine.

5. The method of claim 4 in which the d-isomer is d-thyroxine.
